UNITED STATES PATENT OFFICE

LEO F. DALTON, OF TERRE HAUTE, INDIANA

BOTTLE CLOSURE

Application filed April 22, 1929. Serial No. 357,055.

The present invention relates to bottle closures and has for its prime object the provision of a device preferably made of a yieldable or flexible material such as rubber which is particularly adapted for use in connection with milk bottles taking place of the usual paper caps after said caps have been removed and also to be placed on empty bottles when the same are put out for the collection or by milkmen in order that notes, tickets, money or the like may be conveniently held for the attention of the milkman.

A still further very important object of the invention resides in the provision of a closure of this nature which may be manufactured at an exceedingly low cost, may be distributed as an advertising novelty and will prove thoroughly efficient for the purpose intended.

With the above and numerous other objects in view as will appear as the description proceeds, the invention resides in certain novel features of construction, and in the combination and arrangement of parts as will be hereinafter more fully described and claimed.

In the drawing:

Figure 1 is a sectional view through the upper portion of the neck of a milk bottle showing one of my improved devices therein,

Figure 2 is an elevation of the improved device, and

Figure 3 is a top plan view thereof.

Referring to the drawing in detail it will be seen that the numeral 5 denotes a cap like body in the form of a disk, the upper surface *a* of which is convexed and may be used for advertising purposes and at the uppermost point this upper surface *a* merges into a relatively narrow cylindrical riser 6 formed with a vertical slit 7 so that a card 8, ticket, advertising matter, sign, money, etc., may be placed therein.

The cap like body 5 may be engaged in the neck of the milk bottle similar to the ordinary paper cap and as is illustrated in Figure 1. It is preferable to construct this device as a yieldable or flexible material such as rubber. Obviously these devices may be

constructed very cheaply and because of the advertising matter thereon can be distributed as advertising novelties and used by the housewife or others for closing the milk bottle after the usual paper closures have been removed and also for the purpose of holding tickets and the like when the bottles are set out for collection by the milkman so that notes or the like may be delivered to the milkman as to the amount of milk to be left.

Obviously the device may be capable of other usages which it is not necessary to detail here.

It is thought that the construction, utility and advantages of the invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction may be resorted to without departing from the spirit or scope of the invention as hereinafter claimed or sacrificing any of its advantages.

Having thus described my invention, what I claim as new is:

1. In a bottle closure of the class described, a thickened disk-shaped cap with an extension rising therefrom adapted to be received within and completely cover the bottle, said extension having a slit therein for the reception of a card.

2. In a bottle closure of the class described, a thickened disk-shaped cap of yieldable and flexible material with an extension rising therefrom adapted to be received within and completely cover the bottle, said extension having therein a slit for the reception of a card.

3. In a bottle closure of the class described, a thickened disk-shaped cap of yieldable and flexible material with an extension rising therefrom adapted to be received within and completely cover the bottle, said extension having therein a slit for the reception of a

card, the upper surface of the cap being convexed and adapted to receive advertising matter.

4. In a bottle closure of the class described,
5 a thickened disk-shaped cap of yieldable
and flexible material with an extension rising
therefrom adapted to be received within and
completely cover the bottle, said extension
having therein a slit for the reception of a
10 card, the upper surface of the cap being con-
vexed and adapted to receive advertising
matter, said extension being cylindrical and
having a slit vertically and diametrically dis-
posed with respect thereto for the reception
15 of a card.

In testimony whereof I affix my signature.
LEO F. DALTON.
